(57) **CLAIM**

The ornamental design for a convertible tailgate table, as shown and described.

DESCRIPTION

FIG. 1 is a front perspective view showing a convertible tailgate table;

FIG. 2 is a rear perspective view thereof;

FIG. 3 is first side view thereof;

FIG. 4 is a second side view thereof;

FIG. 5 is a front view thereof;

FIG. 6 is a rear view thereof;

FIG. 7 is a top view thereof;

FIG. 8 is a bottom view thereof; and,

FIG. 9 is an alternate view showing convertible tailgate table in a nested position.

The broken lines depict portions of the convertible tailgate table that form no part of the claimed design.
